DISTRIBUTOR HEAD AND CONDUCTOR FOR
INTERNAL COMBUSTION ENGINES

James Aubrey Burckhalter, Barnwell, S. C.

Application November 30, 1939, Serial No. 306,787

2 Claims. (Cl. 200—19)

This invention relates to distributors for internal combustion engines and particularly to an improved distributor head and set of conductor-carrying tubes, an object being to provide an improved construction of a distributor head wherein in the head and coverings or tubes of the conductors are integral or substantially integral.

Another object of the invention is to provide a head for a distributor to be used with internal combustion engines wherein the wires leading to and from the head are provided with rubber or other insulating covering integral with the distributor head.

In the accompanying drawing—

Fig. 1 is a vertical sectional view through a distributor head and conductor structures disclosing an embodiment of the invention, the section being taken approximately on the line 1—1 of Fig. 2;

Fig. 2 is a sectional view through Fig. 1 approximately on the line 2—2.

In internal combustion engines, particularly in automobile engines, a distributor is provided for distributing the electric current to the spark plugs at the proper time. Each of these distributors is provided with a removable head and the practice heretofore has been to provide removable conductors formed to be removably connected with the spark plugs and also removably connected to the distributor head. However, where removable heads provided with removable conductors have been used there is an eventual loss of current flow to the spark plugs caused by corrosive action followed by arcing at the point where the removable conductor is inserted into the wire receptacle of the head. Where such current loss exists it is possible to correct the condition by removal of the conductor and cleaning of the metal surfaces, but to obviate the necessity for such cleaning and to eliminate the cumulative effects of corrosion and arcing between cleanings it is hereby proposed to remove the cause of such current loss by constructing the distributor head and conductors in one integrally formed unit.

As shown in Fig. 1, 1 indicates the distributor head which is made of some desired plastic material, as for instance rubber or "Bakelite." Preferably the head 1 is made of rubber and is vulcanized until it is comparatively hard. Extending from the upper surface of the head 1 are a number of tubes 2 arranged near the periphery and a central tube 3 arranged centrally of the head. As the tubes 2 and 3 are rubber and the head 1 is rubber, they may be formed integral as shown in Fig. 1, but when being vulcanized the head 1 is vulcanized until it is hard while the tubes 2 and 3 are vulcanized until they

are resilient. The tube 3 accommodates the lead-in wire 4 extending from the spark coil while the various tubes 2 accommodate the various lead-out wires 5. The lead-out wires at their free ends may be provided with any suitable form of contacts to be removably connected to the respective spark plugs of the engine. In the structures shown in Figs. 1 and 2, there are provided six lead-out wires for a six-cylinder engine but it will be evident that more or less could be provided without departing from the spirit of the invention. From Fig. 1 it will be seen that the wires 4 and 5 extend through their respective tubes and into the upper part of the head 1. Wire 4 is connected with a metal block, contact or segment 6 embedded in the head 1 and with a contact member 7 which receives the center contact of the distributor. The various wires 5 are welded or otherwise rigidly secured to metal blocks, contacts or segments 8 having contact surfaces 9 of the usual kind found in distributing heads now in common use. The head 1 at the lower part may be provided with a stiffening flange 10 and clamp-receiving ears, lugs or projections 11 and 12. These members are of the usual kind and shape and also are positioned at the usual place so that the head 1 may be applied to distributors now in use. By the construction just described, in case the tubes 2 become wet from rain or from any other reason, none of the water can pass downwardly into the distributor head to cause short-circuiting.

The wires 4 and 5 by reason of the structure just described in the various forms of the invention cannot be removed from the head but their free ends are intended to be removably connected with the spark plugs in the usual way of wires of this kind.

I claim:

1. In a distributor for internal combustion engines, a distributor head comprising a hard rubber body having a plurality of flexible rubber tubes integral therewith, there being a central tube and a plurality of peripheral tubes, a wire extending through each of said tubes into said body, and a metal contact for each of said wires embedded in said hard rubber head and extending inwardly therefrom.

2. A distributor head of the character described including a body formed of hard plastic material and tubes integral with the body formed resilient, a contact member having a portion thereof embedded in said head opposite each of said tubes, and a wire extending through each of said tubes and into electrical connection with said contact members.

JAMES AUBREY BURCKHALTER.
